UNITED STATES PATENT OFFICE.

EDWIN H. MESSITER, OF NEW YORK, N. Y.

FURNACE-CHARGING APPARATUS.

No. 840,573.

Specification of Letters Patent.

Patented Jan. 8, 1907.

Application filed February 7, 1905. Serial No. 244,676.

To all whom it may concern:

Be it known that I, EDWIN H. MESSITER, a citizen of the United States, residing in the city, county, and State of New York, have 5 invented a new and useful Furnace-Charging Apparatus, of which the following is a specification.

This invention relates to furnace-charging apparatus, and more especially to apparatus 10 for charging copper and lead smelting furnaces, the object of the invention being to provide an apparatus by means of which a smelting-furnace may be economically charged with the employment of a minimum 15 amount of hand-labor and the charge so supplied to the furnace and so distributed therein that thoroughly satisfactory results may be obtained in the operation of the furnace.

With this end in view the invention comprises means for supplying one or more streams of the charging material to the furnace and means for automatically distributing the material to a furnace in the manner best suited to the conditions obtaining at any 25 time in the furnace.

In the accompanying drawings I have illustrated one embodiment of the invention, which will be hereinafter described in detail, it being understood, however, that various 30 changes in the details of construction may be made without departing from the spirit of the invention, the scope of which is clearly defined in the appended claims.

In the drawings, Figure 1 is a fragmentary view, in side elevation, of the upper portion of a smelting-furnace of the ordinary rectangular form, provided with charging apparatus constructed in accord with the present invention, parts of the furnace structure and the 35 charging apparatus being broken away to economize space. Fig. 2 is a fragmentary view, partly in elevation and partly in section, of the structures illustrated in Fig. 1. Fig. 3 is a view in side elevation of the preferred form 40 of mechanism for imparting periodic movement to the distributing devices within the furnace. Fig. 4 is an elevational view of the structure shown in Fig. 3, taken in a plane at right angles to the plane of Fig. 3, a part of 45 the structure being broken away to show the internal construction. Fig. 5 is a diagrammatic plan view, on a small scale, showing a furnace provided with charge-distributing devices on each side and means for imparting movement in opposite directions to the 50 charge-distributing devices simultaneously. 55

As is well known to persons skilled in the art, the common practice in lead and copper smelting in America is to employ furnaces of rectangular cross-section, in which the horizontal dimensions of the furnace in directions at right angles to each other are ordinarily in approximately a ratio of one to two or more. It is for furnaces of this character 60 that the charging apparatus forming the present invention is primarily designed, and the charging apparatus may be applied to such furnaces without altering the structure except above the charging-floor.

Referring to the drawings, F designates 65 the furnace-shaft, and C designates the charging-floor. The hood of the furnace, through which the fumes pass to the flues, is designated H, and it extends upward above the level of the charging-floor. A stack-flue S extends 70 upwardly and to the right from the furnace-hood.

On each side of the furnace and above the top of the furnace-shaft proper there is arranged a track consisting of rails 1 1, as shown 75 in Fig. 2. Beneath each of these tracks an inclined wall 2 extends from the base of the outer rail of the track to the top of the side wall 3 of the furnace-hood, and the space between the top of each side wall of the hood 80 and the base of the inner rail of the corresponding track is left open, for reasons that will hereinafter appear. On the rails 1 1 of each of the tracks I provide a car 4, provided with suitable flange-wheels 5, which rest 85 upon the rails, the body of the car being suspended beneath the axles upon which the wheels are journaled, and on each car and extending downwardly therefrom is a hopper 6, from the bottom of which an inclined chute 7 extends into the upper portion of the furnace. The bottom of each chute 7 lies substantially parallel with the adjacent inclined 90 wall 2, and the lower end of each chute projects inwardly a short distance beyond the 95 side wall 3 of the furnace.

Pivotal mounted on trunnions midway between the axles of each car is a tapering conduit or chute 8, which is preferably of rectangular cross-section. The conduit or chute 100 8 has its lower end disposed above the hopper 6, which is sufficiently wide to receive the material passing through the conduit or chute in whatever position it may occupy. The upper end of each conduit or chute is considerably wider than its lower end, and it receives the lower end of a stationary spout 9,

as best shown in Fig. 1. Each spout 9 is preferably provided near its lower end with a pair of rollers 10, mounted on opposite sides thereof and supported in any suitable manner, as by brackets 11. The rollers 10 engage guide-strips 12, placed at the margins of slots 13, formed in the sides of the chutes or conduits 8, and, as will presently appear, the rollers permit the oscillatory movement of the said chutes or conduits about the lower ends of the spouts 9.

As shown in Fig. 1, the rails 11, that form the tracks at the sides of the furnace-shaft, extend outwardly beyond the end walls of the furnace to a considerable distance, and at each end of each car 4 I provide a cover-plate 14, which is sufficiently long to form, with the car, a cover for the open space above each of the inclined walls. The cover-plates 14 are preferably provided with suitable rollers 15, which rest upon the rails 11 and support the plates in proper position.

In order that the two cars 4 may move in unison and also in order that the chutes 7 may be properly braced, I preferably provide connecting-rods 16, extending transversely of the furnace between the two chutes to which they are secured. Each chute, therefore, is securely connected with the other, and each serves as a brace for the other.

In the operation of the apparatus described in the foregoing the furnace-charging material is supplied through the stationary spouts 9, which, as shown in Fig. 2, converge over the furnace-hood H and are connected with a hopper 17, into which material is continuously deposited by any suitable conveyer apparatus—such, for example, as a belt conveyer. The material flowing into the hopper 17 is divided into two streams which descend through the spouts 9 and pass into the open upper ends of the chutes or conduits 8, through which they pass to the hoppers 6 and thence through the inclined chutes 7 into the furnace.

If the inclined chutes 7 were allowed to remain stationary, the material passing through them into the furnace would not be properly distributed, and in order to insure proper distribution of the charging material in the furnace reciprocal movement is imparted to the cars 4, from which the chutes 7 are suspended. For imparting this reciprocal movement I preferably make use of the apparatus now to be described, by means of which I am able to produce at will a reciprocal movement of the cars at uniform speed throughout the entire length of the furnace or to produce a reciprocal movement which is more rapid adjacent to one end or to the other, as may be desired.

As is well known, it is a desideratum in lead and copper smelting to keep the top of the charge in the furnace tolerably level and cool, and as the rate at which the charge de-

scends in different parts of the furnace-shaft may vary, owing to various conditions, it is necessary for proper mechanical feeding of the charge to the furnace to provide means for feeding the charging material more rapidly sometimes at some points than at others. It is also desirable to provide for the distribution of the fine and coarse particles of the charge in certain relative proportions in different parts of the furnace, the most commonly-used plan of distribution being to deposit the greater portion of the fine constituents of the charge near the side walls and the greater portion of the coarse constituents near the median line. The desired conditions mentioned, including the variation of the rate of feed to different parts of the furnace and the relative distribution of the coarse and fine particles of the charge, are obtained by the apparatus forming the present invention. The inclined chutes 7 effect the deposit of the fine particles near the sides of the furnace and the coarse particles or lumps near the median line, as will be readily seen. The fine particles naturally slip more slowly along the bottom of the chute than the coarser particles, and consequently they pass out of the chute with less velocity and fall more directly downward, while the coarser particles rolling freely down the chute are carried farther from the side walls of the furnace and are for the most part deposited near the middle of the furnace.

The apparatus for imparting reciprocatory movement to the cars 4 and for producing correspondingly oscillatory movement of the conduits 8 is shown on a small scale in Fig. 1 and on a larger scale in Figs. 3 and 4. Referring to the latter figures, 18 designates a framework which is arranged vertically and which may be at any suitable distance from the furnace. In this framework the main shaft 19 is journaled in suitable bearings 20, and a heart-cam of peculiar form is fastened upon the shaft. Rotary movement at slow speed is imparted to the shaft by a worm 22, driven in any suitable manner, and a worm-gear 23, with which the worm 22 meshes. The cam 21 is considerably larger at one end than the other, as clearly shown in the drawings, and about midway between the ends its circumference is of the exact form required to impart reciprocatory movement at uniform speed to the member actuated thereby. Arranged for reciprocatory movement in the frame 18, above the cam 21, is a smaller frame 24, provided at its sides with suitable projections 25, which engage with corresponding guides in the frame 18 and insure the vertical reciprocation of the frame 24. At the bottom the frame 24 is provided with a pair of parallel threaded shafts 26, each of which is provided at one end with a sprocket-wheel 27, the two sprocket-wheels being connected by an endless chain 28, running over them

in the usual manner. A crank 29 upon one threaded shaft serves to impart rotation thereto when desired, and through the medium of the sprocket-wheels and chain a corresponding rotation is imparted to the other shaft. Mounted on a pair of threaded blocks 30, which are carried by the shafts 26, is a downwardly-curved yoke 31, in the middle of which is rotatably mounted a roller 32, which is engaged by the cam 21. On a shaft 33, carried by the frame 24, there are mounted a plurality of pulleys 34, the number being adapted to the amount of movement to be produced in the cars 4 and to the size of the cam 21. On the shaft 35 in the lower part of the frame 18 a corresponding number of pulleys 36 are mounted, the shaft 35 being preferably disposed in a vertical plane at a slight angle to the vertical plane of the shaft 33. Over the pulleys 34 and 36 a cable 37 is rove, one end of the cable being attached to the frame 24, as by a staple 38, and the other end of the cable being carried around a guide-pulley 39 to two branches, each attached to the end of one of the cover-plates 14, carried by one of the cars 4. To the end of the other cover-plate 14, carried by each of the cars 4, is attached one end of a cable 40, which passes over a guide-pulley 41 and has a counterweight 42 suspended at the free end of the cable.

By imparting movement to the worm 22 a slow rotation will be imparted to the worm-gear, to the main shaft 19, and to the cam 21. This movement of the cam will of course produce vertical reciprocatory movement of the frame 24 in its guides, and if the yoke 31 be so adjusted by means of the threaded shafts 26 as to bring the roller 32 into a position midway between the ends of the cam 21 the frame 24 will move with uniform speed throughout its entire movement, and the cars 4 will travel at uniform speed to and fro along the tracks at the sides of the furnace. As the charging material is supplied to the hopper 10 at a uniform rate, the distribution of the charging material in the furnace will depend solely upon the rate of movement of the cars 4 and the structures carried thereby, and a uniform movement of the cars will produce a uniform distribution of material along each side of the furnace. If, however, the charge sinks more rapidly near one end of the furnace than near the other, it will be desirable to modify the rate of travel of the cars to produce more rapid movement near one end of the furnace and slower movement near the other, thus allowing more of the charging material to be deposited near the end of the furnace where it is needed. To bring about this result, the threaded shafts 26 may be turned to bring the yoke 31 and roller 32 nearer to the small end of the cam 21, while if it is desired to supply more material near

the other end of the furnace the yoke 31 and roller 32 may be shifted to the larger end of the cam.

In furnaces where a uniform feed in all parts of the furnace is desired at all times, as in furnaces of comparatively small dimensions, the arrangement of the devices for imparting movement to the cars diagrammatically illustrated in Fig. 5 may be employed. In that view the cables 40 at the ends of the cars are replaced by a cable 40^a, connecting the two cars and passing around guide-pulleys 41^a, and instead of having both cars connected with a reciprocating mechanism a cable 37^a extends directly from the reciprocating mechanism to one of the cars, and a counterweight 42^a is connected with the other car by means of a cable 43, which passes over a suitable guide-pulley 44.

From the foregoing description and the drawings illustrative thereof it will be readily seen that by means of the feeding apparatus forming the present invention it is not only possible to effect the charging of blast-furnaces without the employment of manual labor to any considerable extent, but the feeding obtainable by mechanical means is susceptible of regulation to meet varying conditions, and much greater certainty in the feeding can be obtained than with hand-labor, as it is possible to eliminate altogether the uncertainties which will always exist where the judgment and conscientiousness of the workmen are important factors in the production of the result.

While I have described a single embodiment of my invention only, it will be readily understood that various changes therein may be made by the exercise of the ordinary mechanical skill of persons skilled in the art, and I do not therefore limit myself to the actual structure disclosed, but reserve the right to make changes therein within the scope of the appended claims.

Having thus described my invention, what I claim as new, and desire to secure by Letters Patent, is—

1. In furnace-charging apparatus, the combination with means for supplying and maintaining a stream of charging material, of deflecting devices having periodic movement in a single vertical plane for deflecting the stream of charging material to different parts of the furnace.

2. In furnace-charging apparatus, the combination with means for supplying charging material, of means for automatically effecting the distribution of the charging material to the furnace so that different amounts of material will be supplied to different portions of the furnace.

3. In furnace-charging apparatus, the combination with means for supplying charging material, of material-distributing devices,

and means for imparting periodic movements to said distributing devices in a single vertical plane.

4. In furnace-charging apparatus, the combination with means for supplying charging material, of means for mechanically controlling the distribution of charging material to different parts of the furnace so that different amounts of material are automatically supplied to different parts of the furnace.

5. In furnace-charging apparatus, the combination with means for supplying a stream of charging material, of means for shifting the point of delivery of said stream of charging material, and means for automatically controlling the movement of said point of delivery so that unequal amounts of material will be delivered to different parts of the furnace.

6. In furnace-charging apparatus, the combination with means for maintaining a flow of charging material to the furnace, of means for deflecting the flow of material to different parts of the furnace and automatic devices whereby the movements of said deflecting means may be controlled so as to effect the delivery of unequal amounts of material to different parts of the furnace.

7. In furnace-charging apparatus, the combination with means for supplying charging material, of a receptacle to receive the supply of charging material, and distributing devices beneath said receptacle arranged for periodic movement in a single vertical plane, whereby a stream of material from said receptacle to the furnace is maintained and its direction periodically changed.

8. In furnace-charging apparatus, the combination with a furnace having a shifting charging-opening, of means for maintaining a flow of charging material through said opening, and means for automatically controlling the rate of shifting of said charging-opening, so that unequal amounts of charging material will be supplied to different parts of the furnace.

9. The combination with a smelting-furnace having an elongated charging-opening, of a distributor for charging material arranged to discharge through said opening and having a reciprocatory movement lengthwise of said opening, of a chute or conduit leading to said distributor and having its lower end secured thereto, the upper end of said chute or conduit being arranged to receive material discharged at a fixed point.

10. The combination with a smelting-furnace having an elongated charging-opening of material-distributing devices comprising a carriage external to the furnace and arranged for reciprocatory movement lengthwise of said charging-opening and an inclined chute extending downwardly from said carriage and through said charging-opening, shields at both ends of said carriage and of

sufficient length to keep said charging-opening closed in any position of said carriage, means for supplying a stream of charging material and means for deflecting said stream of charging material from a fixed point to said carriage during the reciprocatory movement of said carriage and directing said stream of material into said inclined chute.

11. The combination with a smelting-furnace having a charging-opening on each side near the top, of a pair of material-distributors arranged for reciprocatory movement at the sides of said furnace, so as to effect the delivery of material into the interior of said furnace, a material-receiving hopper above said furnace having divergent discharge-chutes, and means for directing the streams of material from said discharge-chutes to said distributors during the reciprocatory movement of said distributors.

12. The combination with a smelting-furnace having an opening at the top thereof, of a hopper arranged for horizontal travel with respect to said opening, an oscillatory chute pivotally connected at its lower end with said hopper so as to discharge thereinto, means for moving said hopper to and fro with respect to said opening, and means at the top of said chute for discharging material thereinto.

13. The combination with a smelting-furnace of a fixed hopper, a traveling hopper at a lower level than the fixed hopper and having a chute leading to the furnace, and a chute pivoted at its lower end on the traveling hopper and having its upper end supported by suitable guiding devices so that material passing from the fixed hopper will pass into the last-named chute when the traveling hopper is in any position.

14. The combination in charging apparatus for a smelting-furnace, of a movable distributor for charging material and mechanism for imparting reciprocatory movement to said distributor, said mechanism comprising a heart-cam and a member engaging the surface of said cam and connected with said distributor.

15. The combination in charging apparatus for a smelting-furnace of a movable distributor and mechanism for imparting periodic movement to said distributor, said mechanism comprising a heart-cam, a traveling structure moving in guides and having a part in contact with said cam, and connections between said structure and said distributor.

16. The combination in charging apparatus for a smelting-furnace of a movable distributor for the charging material and mechanism for imparting periodic motions to said distributor and comprising a heart-cam tapering from one end to the other and of the exact contour intermediate of its ends to impart uniform reciprocatory movement to a member engaging the cam, a traveling structure to which motion is imparted by the ro-

tation of said cam, a roller carried by said traveling structure and engaged by said cam, said roller being adjustable between the ends of the cam.

- 5 17. The combination in charging apparatus for a smelting-furnace of a distributer for the charging material and mechanism for imparting periodic movement to said distributer, said mechanism comprising a cam and a structure to which reciprocatory movement is imparted by said cam, a pulley mounted on a fixed axis, and a pulley carried by said structure, and a cable rove over said pulleys and connected with said distributer.
- 10 18. The combination in furnace-charging

apparatus of an endless conveyer, a fixed receiving-hopper into which said conveyer delivers, a distributer arranged for reciprocatory movement adjacent to said furnace so as to deliver material thereinto throughout its 20 movement and shiftable members for conducting the material delivered from said receiving-hopper to said distributer during the movement of said distributer.

In testimony whereof I affix my signature 25 in presence of two witnesses.
